CARRIER FOR SMALL GAME

Harry J. Caughren, Osakis, Minn.

Application December 23, 1940, Serial No. 371,232

1 Claim. (Cl. 224—7)

This invention relates to game holders or carriers, and particularly to such devices adapted to be supported from the clothing of the hunter and to securely hold and carry small game by the neck or legs.

It is an object of my invention to provide a simple, inexpensive game carrier adapted to be readily connected with or supported from an article of clothing such as a belt, a loop, or an edge of a pocket or pair of trousers, and which will effectively retain the game at the hips and thighs of a hunter without interfering with his walking, aiming and other movements.

More specifically, it is an object to provide a game holder and carrier in the form of a simple, integrally constructed device formed to provide a retaining element for connection with a belt or other supporting portion of a hunter's clothing, and formed also to provide a substantially vertical, narrow, slotted member having an open entrance portion at its upper end for receiving the necks and legs of small game, whereby the game will be securely held between the opposing sides of the slotted member with the natural enlargements of the game, such as the head or feet, positively retaining the game from displacement.

Another object is to provide in such an integral device projecting means adjacent the throat or entrance of the holder proper to prevent upward disengagement of the game from the confines of the slotted portion.

Still another object is the provision of readily detachable means for engagement with a belt, loop, pocket or other upwardly extending edge to support the holder.

It is another object to provide a small, compact holder for small game which may be conveniently worn at or adjacent the hips of the hunter, and which is of such size and shape that a number thereof may be simultaneously utilized without seriously interfering with hunting operations and in which fowls or other small game as they are shot may be readily and easily secured and held while the hunter is standing or walking.

These and other objects and advantages will be more apparent from the following description made in connection with the accompanying drawing, wherein like reference characters refer to the same parts throughout the several views, and in which:

Fig. 1 is a fragmentary perspective view showing one of my game holders and carriers attached to the belt adjacent the hip of the wearer;

Fig. 2 is a side elevation of one form of my game holder detached, and

Figs. 3 to 11, inclusive, are similar views of somewhat different forms of the invention.

In the form of the invention shown in Figs. 1 and 2, the holder device 15 is bent or otherwise formed in the shape shown from an integral piece of material such as a stiff wire or rod, preferably capable of being bent into shape with proper tools and possessing a considerable degree of resiliency. The device comprises a narrow retaining loop 15a which may be bent from the upper end thereof, having an open and converging entrance throat 15b to facilitate engagement of the loop with a belt, pocket or upstanding edge such as the top of a pair of trousers. The slot formed by the loop is diminished preferably adjacent the entrance portion to provide for resilient clamping action when the device is attached to and supported from the edge of a piece of clothing.

The body 15c of my game holder 15 is straight and extends downwardly for some distance below the loop 15a forming the shank of a hook-shaped game retainer 15d, which may be conveniently constructed by bending the lower end of the rod or wire upwardly, and which preferably has its upper extremity bent outwardly at 15e. It will be noted that the shank portion 15c and hook portion 15d of member 15 define a relatively narrow slot S which is slightly wider at its upper and open portion than at its lower portion, tapering in width from top to bottom. The entrance to this slot between the two turned extremities of the rod or wire is of sufficient clearance to enable the neck portion of most game fowls to be readily passed therethrough to cause the neck to be engaged with the slotted member. The width of the slot S is sufficiently narrow to prevent slippage of the head therethrough and the game is thus retained within the confines of the hook shaped portion. The element 15d may be sprung out somewhat with reference to the shank portion 15c in the event the legs or necks of game animals are too large for reception by the entrance portion of the device.

In use the narrow retaining loop 15a may be quickly slipped over a belt, an edge of a pocket or the upper waist band of a pair of trousers or other upstanding edge, and is preferably disposed adjacent the hips of the wearer. Two or three of these devices may be worn about each hip without inconvenience. In attaching my game holder 55 the hook portion constituting the game holder

proper, is disposed outwardly for convenience of attaching game.

Fig. 1 illustrates the manner in which a duck is positively secured within the confines of the hook-shaped element, the weight of the body, of course, placing the strain upon the thicker head of the fowl and the neck only being disposed in the slotted portion. The hook-shaped part of the device is purposely relatively short to prevent interference with the legs and hips during walking or other movements of the hunter, but in view of the relatively small diameter of the game animal's neck or leg near the foot, several of such animals may be secured and effectively held by the device.

The construction and positioning of the outwardly bent extremity 15f of the loop portion 15a at the upper end of the slot prevents accidental displacement or disengagement of the game upwardly when the hunter is sitting down or in position where the body of the game would be urged in an upward direction. The game may be readily detached from the slot-forming-confining hook by pressing the neck against the outward hook portion 15d and, if necessary, slightly bending the same outwardly, the resiliency of the rod or wire from which the device is constructed causing the hook portion to return to normal position. The device is relatively short, very compact and a number may be carried in the pocket of a hunting coat and attached to the belt as needed. They extend downwardly from a belt or top of the upper trousers edge only a short distance and do not in any way interfere with walking, stooping or other movements of the hunter.

In Fig. 3 a slightly different form of the invention is shown wherein the confining hook and all parts of the device are similar to the form shown in Fig. 2, with the exception that the elongated loop 16a is closed, the extremity of the upper piece of the rod being inturned to form an abutment 16f which has the function of the out-turned extremity 15f in Fig. 2 in preventing displacement of game from the retaining hook.

In Fig. 4 the length of the device is somewhat shorter than that of the forms previously described, the hook portion 17d extending nearly to the top of the retaining loop. Also it will be noted that the retaining loop 17a is reversed in relation to the loop of the device 15, shown in Fig. 2, being disposed rearwardly of the confining hook. This device is somewhat better adapted for attachment to the edge of a pocket or the upper waistband edge of a pair of trousers.

In Fig. 5 the device 18 is essentially similar to the device shown in Fig. 2, the difference, however, being in that a more restricted abutment or closure is formed for the entrance throat of the slot S. The outward hook portion 18d has its upper extremity 18e bent inwardly into close relationship with the outwardly turned extremity 18f of the elongated retaining loop. With this device in all cases to insert the neck or leg of a small game animal, the part 18d must be resiliently flexed outwardly.

The form shown in Fig. 6 is similar to the form shown in Fig. 2, with the exception that the extremities of the rod or piece of material from which the device is made are curled or circularly bent at points 19f and 19e to better facilitate the entrance of the neck or legs of an animal into the confining slot.

In Fig. 7 a somewhat different form is shown essentially similar to the form shown in Fig. 4,

but having, however, the elongated loop 20a closed at its lower portion by inwardly bending the upper extremity of the material while the other extremity of the material is bent inwardly at 20e to form an abutment for preventing displacement of game from the carrier. In this form, as in the form shown in Fig. 5, the hook portion 20d must always be flexed outwardly for insertion of the neck or legs of an animal.

10 The form shown in Fig. 8 is similar to the form shown in Fig. 2, with the exception that the outer hook portion 21d is extended upwardly above the lower end of loop portion 21a and terminates in an outwardly curved extremity 21e cooperating 15 with the opposing bent portion 21f of the loop to assist in guiding an animal into the confining slot and enabling the camming effect to be obtained for springing hook portion 21d outwardly.

The form shown in Fig. 9 is similar to the 20 form shown in Fig. 2 with the exception, however, that the upper end of the hook portion 22d is bent adjacent its upper extremity to form an abutment or detent 22g, forming more of a restriction against upward displacement of the game than in the form shown in Fig. 2.

The form shown in Fig. 10 is similar to the 25 form shown in Fig. 2, with the exception, however, that the hook portion 23d is tortuously bent to provide a series of (as shown, three) concave neck retaining elements 23h, each adapted to individually retain the neck or leg of an animal, and these elements being spaced apart by concave bends or abutments 23g which each restrict upward displacement of the respective animals held.

30 Fig. 11 shows a form wherein the outward hook portion 24d extends above the lower retaining loop 24a and the portion of the loop adjacent the hook is outwardly bent to cooperate with the hook to provide an abutment 24k to prevent upward displacement of the game from the confining slot of the hook.

35 From the foregoing description it will be seen that I have provided an extremely simple, inexpensive and highly efficient game carrier adapted to be readily connected to and supported from a belt, upstanding edge, pocket, loop or other articles of clothing of the hunter and constructed to positively retain small game at the hips and 40 thighs of the hunter.

It will further be seen that the device is compact and so constructed and positioned that it will not impede in any way the free movements of the hunter, nor become entangled with brush 45 or debris, as is the case with many elongated game carriers utilized at this time.

50 It will further be seen that an efficient means is provided in my device for preventing upward movement and displacement of game from the carrier when the hunter sits down or moves in such a way as to normally urge upward movement of the game.

55 It will, of course, be understood that various changes may be made in the form, details, proportions and arrangements of the parts without departing from the scope of my invention.

60 While the carrier of the present invention has been described as a carrier for game, it will, of course, be understood that the carrier can be used for holding and supporting from the belt of the wearer a great variety of articles such as tools, packages, lunch boxes etc. to leave the hands of the wearer free and clear. While in the claim 65 the carrier is referred to as a carrier for small game, it will be appreciated that said terminology

is to be taken to mean a carrier for game as well as for other purposes.

What is claimed is:

A carrier for small game comprising, an integral length of rod material bent at an intermediate portion in the form of a narrow U with the sides of said U being in nearly parallel relationship and cooperatively defining a narrow game holding slot for the reception of the necks or feet of game animals, the upper portion of one of the legs of said U-shaped portion terminating in a free end extending upwardly and disposed some distance below the upper end of the other

leg of the U, the opposite end of the length of material being bent upon itself above said free end and on the side of said length adjacent said free end to constitute a belt receiving loop, said loop being open at its lower portion with the extremity of said loop forming the end being bent outwardly in opposition to the open end of said slot and sufficiently close thereto to prevent accidental removal of game from the game holding slot and to further facilitate an entrance of a belt into said loop.

HARRY J. CAUGHREN.
